UNITED STATES PATENT OFFICE

107,230

DESIGN FOR A PLAQUE

Samuel L. Hefter, Chicago, Ill.

Application September 7, 1937, Serial No. 71,488

Term of patent 3½ years

To all whom it may concern:

Be it known that I, Samuel L. Hefter, a citizen of the United States, residing at Chicago, in the county of Cook and State of Illinois, have invented a new, original, and ornamental Design for a Plaque, of which the following is a specification, reference being had to the accompanying drawing, forming part thereof.

Fig. 2 is a side elevation of the same.

Figs. 3 and 4 are sections on the lines 3—3 and 4—4 of Fig. 1, respectively.

I claim:

The ornamental design for a plaque, as shown.
SAMUEL L. HEFTER.
